UNITED STATES PATENT OFFICE.

CARL E. LINGENFELTER, OF CHICAGO, ILLINOIS, ASSIGNOR TO SCULLY STEEL & IRON COMPANY, OF CHICAGO, ILLINOIS, A CORPORATION.

METAL-SHEARING MACHINE.

SPECIFICATION forming part of Letters Patent No. 746,716, dated December 15, 1903.

Application filed July 9, 1903. Serial No. 164,776. (No model.)

To all whom it may concern:

Be it known that I, CARL E. LINGENFELTER, a citizen of the United States, and a resident of Chicago, county of Cook, and State of Illinois, have invented certain new and useful Improvements in Metal-Shearing Machines, of which the following is declared to be a full, clear, and exact description.

The invention relates to that type of metal-shearing machines in which a pair of co-operating rotary cutters are employed, and more particularly to machines provided with rotary cutters and of such a construction that plates of any width or length may be sheared.

Some of the machines of this class heretofore constructed have employed worm-gearing, which is quite inefficient in transmitting the power to the rotary cutters.

The object of the present invention is to provide an improved construction of such machine in which trains of spur-gearing are employed for driving the cutters; further, to provide actuating mechanism by which the co-operating rotary cutters may be driven with the same peripheral speed in spite of any difference in their size, and also to provide satisfactory means for adjustably mounting one of the driven cutters for shearing plates differing in thickness.

The invention consists in the features of construction, combinations, and arrangement of parts hereinafter set forth, illustrated in the accompanying drawings, and particularly pointed out in the appended claims.

The present improved construction comprises a narrow upright frame upon which the pair of co-operating rotary cutters are suitably mounted, with the cutting-plane of said cutters extending longitudinally of the frame. Separate trains of spur-gearing are provided for driving the separate cutters, said gear-trains being mounted to rotate in planes parallel with the cutting-plane and being arranged, respectively, upon opposite sides of such plane and upon opposite sides of the path of travel of the work, so that a sheet of metal of any width or length may be operated upon. The two gear-trains are preferably connected by a differential compensat-

ing gear, which is driven from a suitable counter-shaft.

In the drawings, Figure 1 is a side view of the improved shearing-machine. Fig. 2 is a front view; Fig. 3, a view of the other side of 55 the machine, and Fig. 4 is a rear view. Fig. 5 is a detail section on the line 5 5 of Fig. 2. Fig. 6 is a detail section on the line 6 6 of Fig. 5. Fig. 7 is a detail section on the line 7 7 of Fig. 5. Fig. 8 is a detail side view of 60 the adjusting mechanism for the lower cutter. Fig. 9 is a detail section on the line 9 9 of Fig. 3. Fig. 10 is a detail view on the line 10 10 of Fig. 9.

The narrow upright frame of the machine 65 comprises upper and lower web-sections 11 and 12. The upper and lower rotary cutters 13 and 14 are mounted at the forward part of the machine-frame, with their inner cutting edges arranged in the plane *a a*, which 70 extends longitudinally of the machine-frame. Laterally-projecting flanges or guides 15 and 16, preferably cast integral with the body of the machine-frame, extend rearwardly from the cutters upon opposite sides of the 75 frame. One section of the sheared metal as it passes rearwardly from the cutters is guided along the lower face 17 of the flange 15, (see Fig. 3,) and the other section of the sheared metal is guided rearwardly along the 80 upper face 18 of the flange 16. (See Fig. 1.) One of the flanges 15 is inclined rearwardly and downwardly, as shown, so that divergent paths of travel for the sheared metal are formed. The flanges 15 and 16, moreover, 85 cross and merge into each other at the rear portion of the machine, thus adding to the rigidity of the frame. Flange 15 extends along the lower portion of the upper web-section 11, while the flange 16 extends along the 90 upper portion of the lower web-section 12, and these web-sections adjacent the paths of travel of the work are offset, as shown most clearly in Fig. 4, upon opposite sides of the cutting-plane *a a*.

The co-operating rotary cutters are driven by separate sets of gear-trains formed of spur-gears preferably mounted to revolve in planes parallel to the cutting-plane. The train of gears for driving the upper cutter is 95 100

- mounted on one side of the frame, above the path of travel of the work, while the gear-train for operating the lower cutter is mounted upon the opposite side of the frame and 5 below the path of travel of the work. The upper and lower cutters 13 and 14 are respectively fixed to the ends of spur-gears 19 and 20 by screws, as indicated in Fig. 7, or in any other suitable manner.
- 10 The gear 19 is mounted to revolve upon a shaft 21, the outer end of which is supported in an offset portion 22 of the upper frame-section 11. The inner end of the shaft 21 is supported by a plate 23, (see Fig. 1,) bolted 15 or otherwise suitably secured in place to the front part of the upper frame-section. A spur-gear 24, mounted to revolve in a recessed portion of offset 22 and meshing with the teeth of the gear 19, is fixed upon a revolvable shaft 25, journaled in suitable bearings in the upper frame-section. A large spur-gear 26, fixed to the outer end of the shaft 25, meshes with the teeth of the pinion 27, (see Fig. 9,) which is driven by one of the members 20 of the differential compensating gearing. In a similar manner the gear 20, connected to the lower rotary cutter, is mounted to revolve a shaft 28, the outer end of which is supported in an offset portion 29 of the lower 25 frame-section 12, the inner end of the shaft 28 being supported by a plate 30, (see Fig. 3,) bolted or otherwise suitably secured to the lower frame-section. The gear 20 is driven through the medium of an idler-gear 31, which 30 meshes with the teeth of a gear 32, fixed upon the inner end of a shaft 33. The gears 20, 31, and 33 revolve, as shown, within a suitable recess formed in the offset portion 29 of the lower frame-section, and the shaft 33 is 35 mounted to revolve in suitable bearings formed in said offset portion. Upon the outer end of the shaft 33 is fixed a large spur-gear 36, which meshes with the teeth of the small gear or pinion 37, formed in piece with or 40 suitably connected to a large spur-gear 38. The latter, together with pinion 37, revolve upon a shaft 39, which is fixed to or held within a suitable laterally-extending offset or support 40, (see Fig. 4,) bolted to the lower frame- 45 section 12. A transverse cross-shaft 41 is journaled in a suitable bearing-boss 42, which extends on opposite sides of the frame and is located between the paths of movement of the separate sections of the sheared metal.
- 50 A pinion 43, fixed to one end of the cross-shaft 41, meshes with the large spur-gear 38, and a pinion 44, fixed to the opposite end, meshes with a large spur-gear 45, connected to the differential gearing.
- 55 The differential or compensating gearing, through which the power is applied to the separate cutters, is of usual construction and comprises (see Figs. 9 and 10) a large intermediate gear 46 and the oppositely-facing beveled gears 47 and 48, all mounted to loosely revolve upon a shaft 49, which is fixed 60 within a suitable support 50, bolted to the

upper frame-section 11. A connecting beveled pinion 51, meshing with the teeth of the beveled gears 47 and 48, is journaled, as 70 shown, upon the intermediate gear 46.

The intermediate gear 46 may be driven in any suitable manner, as by a small pinion 52, fixed upon the end of a shaft 53. The latter is journaled in suitable bearings formed in the upper frame-section and on an offset supporting-arm 54, bolted thereto. A large spur-gear 55, fixed to the opposite end of the shaft 53, meshes with the teeth of a pinion 56, keyed to a shaft 57. The latter is journaled 80 in suitable bearings formed upon the upper end of the frame-section 11 and upon an offset supporting-arm 58, bolted thereto. A pulley 59 is fixed upon the shaft 57, through which power may be applied from a counter-shaft through the medium of a belt.

The beveled pinion 47 on one side of the differential gearing is connected to or formed in piece with the pinion 27, and the beveled pinion 48 upon the opposite side of the differential gearing is connected to or formed in piece with the large spur-gearing 45, so that power is applied equally to rotate the cutters 13 and 14 through the medium of the gear-trains described. The gearing is such 95 that when all members of the differential gearing rotate together the cutters will be driven with the same speed of rotation, and if it is assumed that the gears 27 and 45 were rigidly connected together instead of being 100 independently driven through the medium of a differential gearing the cutters would rotate with the same peripheral speed, provided they were of the same diameter; but it frequently happens that the cutters are not of 105 exactly the same diameter—for example, one may be ground smaller than the other in sharpening—so that even though the speed of rotation of the cutters were the same their peripheral speeds would be different; but by independently driving the separate rotating cutters through the medium of a differential gearing, such as described, power will be applied equally to both cutters, although the speed of rotation of one, if larger, may lag 110 behind that of the other, but the peripheral speed of each in operating upon the work will 115 be the same.

The manner of driving the rotary cutters is advantageous to maintain a uniform shearing action to rapidly sever the metal plate. If the peripheral speeds of the cutter differ a great amount of unnecessary friction is developed, and the heat generated may be even sufficient to draw the temper of the cutters.

It will of course be understood that the gearing described may be widely varied without departing from the essentials of the invention. The differential gearing and pulley-shaft could be located, if desired, below the path of travel of the work and the opposite side of the machine-frame from that shown and described.

To adjust the cutters for shearing metal

plate of different thickness, the shaft 28, upon which the lower cutter 14 and gear 20 revolve, is eccentrically journaled (see Figs. 5 and 7) in the upper ends of the offset portion 5 29 and plate 30, and suitable means are provided for adjustably rotating the eccentrically-journaled shaft, so that cutter 14 and its drive-gear 20 may be raised and lowered. The adjusting means preferably comprises a 10 worm-wheel 60, fixed upon the outer end of the shaft 28 and meshing with the teeth of a worm 61. The latter is journaled but held against longitudinal movement between suitable bearing-blocks 62, fixed to the outer face 15 of the offset 29. The squared outer end 63 of the worm may be turned by a suitable crank or wrench to rotate the eccentrically-journaled shaft 28 and adjust the position of the lower rotary cutter 14 and its drive-gear 20. 20 In order that the gear 31 may properly mesh with gear 20 in any of its shifted positions, it is mounted to rotate upon a laterally-shiftable shaft 64. The latter is supported between the ends of a pair of links 65, swiveled upon 25 the eccentrically-journaled shaft 28, and a second pair of links 66, journaled upon the revolving shaft 33, upon which the gear 32 is mounted. In this manner the lower rotary cutter 14 is rigidly but adjustably supported 30 upon the eccentrically-journaled shaft 28, and the adjustment may be effected without in any way altering the mesh of the gears 20, 31, and 32.

It is obvious that numerous changes may 35 be made in the details of structure without departure from the essentials of the invention.

Having described my invention, what I claim as new, and desire to secure by Letters 40 Patent, is—

1. In shearing-machines, a narrow upright supporting-frame, a pair of coöperating rotary cutters mounted on said frame and arranged with their cutting-plane extending longitudinally thereof, a train of cylindrical spur-gears connected directly to each of said cutters, said gear-trains being located upon opposite sides of the path of travel of the work and arranged to revolve in planes parallel to the 45 cutting-plane, connecting-gearing between said gear-trains and means for actuating same.

2. In shearing-machines, a suitable supporting-frame, a pair of coöperating rotary cutters mounted on said frame, two trains of spur-gears for respectively actuating said cutters mounted upon opposite sides of said frame, a transverse cross-shaft geared respectively to said gear-trains and means for 50 actuating said connected gear-trains.

3. In shearing-machines, a suitable supporting-frame, a pair of coöperating rotary cutters mounted on said frame and arranged with their cutting-plane extending longitudinally thereof, two trains of spur-gears for respectively actuating said cutters mounted upon opposite sides of the path of travel of 55

the work and upon opposite sides of the cutting-plane and arranged to revolve in planes parallel to the latter, a connecting cross-shaft 70 geared respectively to said trains and means for actuating the same.

4. In shearing-machines, a suitable supporting-frame, a pair of rotary cutters, means for guiding the separate sections of the 75 sheared metal in divergent paths extending rearwardly from the cutter along opposite sides of said frame, a transverse cross-shaft journaled at the rear of the machine between the paths of travel of the separate sections of 80 the sheared metal, gearing connecting each end of said cross-shaft and one of said cutters and means for driving said gearing.

5. In shearing-machines, a suitable supporting-frame, a pair of rotary cutters mounted 85 on said frame with their cutting-plane extending longitudinally thereof, means for guiding the sheared metal in paths diverging rearwardly from said cutters along opposite sides of the frame, two trains of spur-gearing mounted on said frame to revolve in planes parallel with the cutting-plane, connected respectively to said cutters and arranged on opposite sides of the cutting-plane 90 and upon opposite sides of the path of travel 95 of the sheared metal, a transverse cross-shaft journaled at the rear of the frame between the paths of travel of the separate sections of the sheared metal, pinions on the ends of said shaft engaging respectively with said 100 separate gear-trains and means for driving said gear-trains.

6. In shearing-machines, a pair of rotary cutters, a differential compensating gearing through which power is applied to both of 105 said rotary cutters and means for driving said compensating gearing.

7. In shearing-machines, a differential compensating gearing, means for actuating the same, and a pair of coöperating rotary 110 cutters geared respectively to separate members of said compensating gearing.

8. In shearing-machines, a differential compensating gearing, means for driving the same separate spur-gears operated by said 115 differential gearing, a pair of rotary cutters and a gear-train extending between each of said cutters and one of said spur-gears.

9. In shearing-machines, a suitable supporting-frame, a pair of rotary cutters mounted 120 thereon, a differential compensating gearing mounted on one side of the frame and upon one side of the path of travel of the work, a transverse cross-shaft geared to one member of said differential gearing, a train 125 of spur-gears connecting the other member of said differential gearing and one of said rotary cutters and a second train of spur-gearing connecting said cross-shaft and the other of said rotary cutters, said gear-trains being 130 located respectively upon opposite sides of the frame and upon opposite sides of the path of travel of the work.

10. In shearing-machines, a pair of coöper-

ating rotary cutters, an adjustable shaft whereon one of said cutters is mounted, means for actuating said cutters and shiftable spur-gearing between said actuating means and 5 said adjustably-mounted cutter.

11. In shearing-machines, a pair of coöperating rotary cutters, an adjustable shaft whereon one of said cutters is mounted, operating-gearing for said cutters comprising a 10 shaft held against lateral shift and laterally shiftable, intermeshing spur-gears connecting the latter shaft and said adjustable shaft.

12. In shearing-machines, a pair of coöperating rotary cutters, an eccentrically-journaled shaft whereon one of said cutters is rotatably mounted, operating-gearing for said cutters and laterally-shiftable intermeshing spur-gears between said operating-gearing and said eccentrically-journaled shaft, said 15 gears being adjustable with said shaft.

13. In shearing-machines, a pair of coöperating rotary cutters, an eccentrically-journaled shaft whereon one of said cutters is rotatably mounted, a stationary shaft, a laterally-shiftable shaft, links supporting the latter and mounted respectively upon said stationary shaft and said eccentrically-journaled shaft, intermeshing spur-gears mounted upon said shafts, drive-gearing for said spur-gears 25 and for the other of said cutters, the cutter on said eccentrically-journaled shaft being fixed to the spur - gear rotatably mounted thereon.

14. In shearing-machines, a pair of coöper-

ating rotary cutters, an eccentrically-journaled shaft, a spur-gear journaled to said shaft to which one of said cutters is fixed, a second stationary shaft, a spur-gear mounted thereon, a laterally-shiftable idler-gear intermeshing with said spur-gears and adjustable 35 with said eccentrically-journaled shaft and means for driving said spur-gears and the other of said rotary cutters.

15. In shearing-machines, a pair of coöperating rotary cutters, an adjustable shaft 40 whereon one of said cutters is mounted and operating means for said cutters comprising a shaft held against lateral shift, drive-gears on said latter shaft and on said adjustable shaft and intermediate connecting-gearing between said gears arranged to shift with said adjustable shaft without changing the gear-mesh.

16. In shearing-machines, a pair of coöperating rotary cutters, an eccentrically-journaled shaft whereon one of said cutters is rotatably mounted, operating-gearing for said cutters comprising a shaft journaled parallel to said eccentrically-journaled shaft and held against lateral shift and extensible gearing 55 between said shaft and said eccentrically-journaled shaft, said gearing being adjustable with said latter shaft.
